DEHUMIDIFIER AND DRIER

Ralph K. Shewmon, Dayton, Ohio, assignor to
General Motors Corporation, Detroit, Mich., a
corporation of Delaware

Application February 27, 1951, Serial No. 213,012

2 Claims. (Cl. 34—77)

1 This invention relates to dehumidifying apparatus.

It is among the objects of the present invention to provide a unitary dehumidifier having dual characteristics, one a rotary drier, the other a regional dehumidifier. As a rotary drier, the dehumidifier extracts moisture from air being circulated through a rotating drum contained within the unitary structure and as a regional dehumidifier, the rotary drier is rendered inoperative and the unit functions to extract moisture from atmosphere drawn from areas surrounding or remote from the unit and again discharged into said area.

A further object of the present invention is to provide the dual purpose dehumidifying unit with simple control means operative to render the rotary drier completely inactive while the unit is functioning to dehumidify atmosphere in surrounding or remote areas.

Further objects and advantages of the present invention will be apparent from the following description, reference being had to the accompanying drawing, wherein a preferred embodiment of the present invention is clearly shown.

In the drawing:

Fig. 1 is a schematic view disclosing the unitary structure containing the rotary drier, the refrigerating device acting as a dehumidifier and the air circulating and flow control devices.

Fig. 2 is a fragmentary, detail view illustrating the motor driven air circulating mechanism and its associated elements.

Referring to the drawings, the dual purpose, dehumidifying unit is shown consisting of a main housing 20, which may be of any desirable shape and in which a drum 21 is rotatably supported. The outer, peripheral wall of drum 21 is perforated and, if found necessary, the end heads of the drum may also be perforated so that air may pass into and through the drum for purposes of drying the contents of the drum. The supporting stub shafts 22 extending axially from each end head, are journaled in suitable bearings provided within the housing 20, the one stub shaft 22 having a pulley 23 attached thereto for receiving belt 24. A cover 25 closes an opening in the housing 20 which makes the drier drum 21 accessible. The drum is provided with any suitable, closable opening, not shown, for the introduction and removal of material to be dried.

Within the housing 20 there is also provided a conduit 30, the two open ends 31 and 32 of which are contiguous to the peripheral surface of the drum at diametrically opposite sides re-

spectively. This conduit 30 contains the dehumidifier 33 and the air circulating apparatus 34.

The dehumidifier 33 is a refrigerating device consisting of a motor driven compressor 35 in communication with a condenser coil 36 and an evaporator coil 37, both coils being in communication with each other through an expansion valve 38. These form a closed circuit for contained refrigerant. The dehumidifier 33 is located within conduit 30 adjacent its opening 31. Directly beneath the dehumidifier 33, the conduit and housing have a funnel shaped opening 39 providing a drain for accumulated water extracted from the air passing over the dehumidifier, said water dripping from the evaporator coil 37.

The air circulating apparatus 34 is located within the conduit 30 adjacent its end 32. This apparatus consists of an electric motor 40, the rotatable shaft 41 of which has the air circulating fan 42 attached at its one end. The shaft 41 extending from the end of the motor 40 opposite the fan 42, has a releasable clutch 43 attached thereto, this clutch being of a standard type purchasable on the open market, and having a part which, when shifted, either connects or disconnects the driven part of the clutch from its driving part. In this instance, the driving part of the clutch is attached to shaft 41 so as to rotate therewith, the driven part of the clutch carrying the pulley 44 which receives the belt 24 also connected with pulley 23 on the drier drum shaft 22. The shiftable part of this clutch, the driven part, is actuated to cause release or engagement of the clutch by an actuator 45 extending to the exterior of the housing. Any suitable circuit controller 50 is electrically connected to the motor 40 and the motor for compressor 35, said controller being operative to render said motors active or inactive. If desired, separate controllers for both motors may be provided.

As thus far described, this mechanism forms a drier for contents of the drum 21. When the fan and compressor motor are rendered active, the drum 21 is rotated by its belt connection with the motor 40 as is also the fan 42. The operating compressor 35 renders the refrigerating device 33 active. Air forced by fan 42 through conduit 30, over the refrigerating device 33, passes from the conduit opening 31 through the perforated drum 21 and over its contents. The moisture laden air passes from the drum 21 through opening 32 into the conduit. This circulating air flow is maintained as long as the fan 42 is driven by motor 40. The refrigerating device, function-

ing as a dehumidifier, extracts moisture from the moisture laden air passing over it on its way to be recirculated through the drum 21, the moisture gathering on the evaporator coil 37 of the dehumidifier 33 and dripping into the drain 39. Thus the air, circulated through the conduit 30 and drum 21, has its moisture content reduced, thereby facilitating and accelerating the drying of the drum contents which may be laundry, grain or any other material from which moisture is to be extracted.

To render the aforescribed mechanism effective for dual dehumidifying purposes so that not only the contents of the rotating drum is dehumidified but surrounding areas or another chamber, separate from the drum, may be dehumidified, means are provided in the unit whereby the drum is circumvented and other areas are brought into cooperating communication with the conduit 30. This feature is accomplished by providing communicating ports or openings 60 and 61, in the housing 20 and conduit 30. Port 60 is located so as to communicate with the interior of the conduit behind fan 42 and between said fan and the opening 32 of the duct. The other port 61 opens into the duct between the dehumidifier 33 and the conduit opening 31. Both ports may be opened or closed by a closure member hingedly secured to the housing or conduit wall, port 60 by the closure member 62 and port 61 by the closure member 63. When said closure members cover their respective ports, as illustrated in Fig. 1, the unit operates as a drum content dehumidifier. It will be noted that when said closure members 62 and 63, respectively, are moved into their dot and dash line position as illustrated in Fig. 1, their respective ports 60 and 61 are opened and each member functions as a damper, member 62 closing the conduit adjacent its opening 32 and member 63 closing the conduit near opening 31. When the fan 42 is operated with members 62 and 63 so acting as dampers, air is drawn from the area outside housing 20, through port 60 into conduit 30 and forced through said conduit, over the dehumidifier 33 and out through port 61 into the said area exterior of the housing. The drum 21 is completely isolated and no air is circulated therethrough.

When the unit functions as a dehumidifier for atmosphere exterior of the housing 20, it would be undesirable and impractical to actuate the drum 21. Therefore the pulley 43, driven by the fan motor 40 and drivingly connected to the drum pulley 23 by belt 24, is releasably secured to the shaft 41 of said motor 40 by any suitable, standard releasable clutch mechanism, interposed between the pulley 43 and motor shaft 41. This clutch mechanism is controlled by an actuator 45 extending through the housing to the exterior thereof so as to be readily accessible.

Thus when the unit is to be used as a drier for material within the drum 21, ports 60 and 61 are closed by the respective closure members 62 and 63, thereby removing the restrictions in the conduit provided by said members 62 and 63 when in their port opening positions. The actuator 45 is moved to adjust the clutch so that pulley 43 is operatively connected to shaft 41 and the former will be rotated with the latter and thus said rotating pulley 43 will drive the drum 21 through belt 24 and the pulley 23 on the drum shaft 22. The controller or switch 50 is actuated to render the fan motor and compressor motor active so that the air is circulated

by the fan 42, through conduit 30, over the refrigerator or dehumidifier 33 and through the perforated drum 21.

When the area outside the housing is to be dehumidified, ports 60 and 61 are again opened which causes their respective closure members to be moved into positions in which they shut off communication between the conduit 30 and the drum 21, thus isolating the drum. The clutch in pulley 43 is adjusted to release the pulley from the motor shaft and render said pulley inoperative by said shaft whereby the drum remains inactive. The fan, when rotating, draws air from the outside area, into the conduit, forces it through the conduit over the dehumidifier and out of the unit through port 61.

From this it may be seen that in the present invention a unitary dehumidifier is provided, having means adjustable to convert said unitary structure from a rotary drier into a dehumidifier for areas surrounding or remote from the unit itself. The two ports 60 and 61 may be connected by ducts with other drying units separate from the unit supplied with the dehumidifying mechanism 33.

A simple operation of clutch and closure members converts a rotating drum drier into a room or exterior chamber dehumidifier, thus giving the unit a dual functional character.

While the embodiment of the present invention as herein disclosed, constitutes a preferred form, it is to be understood that other forms might be adopted.

What is claimed is as follows:

35. 1. As a domestic appliance for use in homes, a self contained single unit clothes drier and room air dehumidifying unit, comprising, a cabinet, a rotatable perforated drum within said cabinet to receive clothes to be dried, an access door in one wall of the cabinet to gain access to said drum for loading the same, partitions within said cabinet compartmenting the interior of the cabinet to form with the walls thereof an air flow duct open at both ends with both open ends closely adjacent the periphery of the drum and encircling a portion of the drum and disposed at substantially opposite sides of the drum, fan means in said duct for circulating air through the same, a refrigerant cooling means and a refrigerant condensing means in said duct in series flow relationship to dehumidify air circulated by the fan through the duct, a wall of said cabinet having an air inlet opening into said duct between said fan and one open end of said duct, a closure member in said duct adjacent said inlet having one position to close said inlet whereby air is drawn into said duct from said drum and a second position to close said duct between the fan and the said one open end thereof whereby air is drawn into said duct through said inlet from the room in which the appliance is positioned, a wall of said cabinet also having an outlet opening from said duct between the position of said cooling and condensing means and the other open end of said duct, a closure member in said duct adjacent said outlet having one position to close said outlet whereby air discharges from the duct into said drum and a second position to close said duct between said other open end thereof and the position of said cooling and condensing units therein whereby air discharges from the duct into the room in which the appliance is positioned, said closure members providing thereby solely for air circulation through said drum when said closure mem-

bers are in the said one position and solely for room air circulation through said duct when the closure members are in the said second position.

2. A domestic appliance in accordance with 5 claim 1 in which the fan and the drum are driven by a single power source.
